E. R. CARICHOFF

MAGNETIC BLOW-OUT

Original Filed Feb. 27. 1920

Fig. 3.

Inventor,
Eugene R. Carichoff,
by *Alvin G. Davis*
His Attorney.

UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

MAGNETIC BLOW-OUT.

Original application filed February 27, 1920, Serial No. 361,694. Divided and this application filed June 29, 1921. Serial No. 481,422.

To all whom it may concern:

Be it known that I, EUGENE R. CARICHOFF, a citizen of the United States, residing at Schenectady, in the county of Schenectady, 5 State of New York, have invented certain new and useful Improvements in Magnetic Blow-Outs, of which the following is a specification.

My invention relates to improvements in 10 magnetic blow outs for disrupting the arcs formed between circuit interrupting contacts. The invention is directed to improvements whereby a reliable and effective magnetic blow out may be manufactured of a 15 comparatively few simple parts which can be quickly assembled and disassembled.

This application is a division of my co-pending application Serial No. 361,694, filed February 27, 1920.

20 For a better understanding of the invention, reference is had to the accompanying drawing in which I have shown an embodiment of the invention for purposes of illustration, and in which Fig. 1 is a side view 25 of an electromagnetic switch in the closed position and provided with a magnetic blow out in accordance with my invention; Fig. 2 is a similar view showing the switch in the open position; and Fig. 3 is a detail 30 showing a front view of the magnetic blow out.

The magnetic blowout for disrupting the arcs formed between the circuit interrupting contacts 21 and 17 comprises a magnetic 35 blow out electromagnet having a winding 27, one terminal of which is connected to the stationary contact 21 and the other terminal of which is connected to the terminal post 28. The other terminal post 29 of the 40 switch is connected to the wiping contact 17 by means of a flexible conductor 30. Metallic plates 31 and 32 which serve as pole pieces for the winding are clamped to the ends of the winding by means of a bolt 27^a, 45 and a block of insulating refractory material 33, having a chute 34 through which the arc stream passes, is removably held between the pole pieces by the clamping action of the bolt. The bolt is screwed into the one end 50 of the core for the winding 27, so as to clamp the pole piece 32 to the core and the pole piece 31 is riveted to the other end of the core. A pin and slot connection between the plates and the arc chute is pro-

vided so as to positively hold the chute in 55 proper position. Thus, an elongated pin or projection 35 is formed on the end of the arc chute and this projection cooperates with a slot of similar shape in the pole piece. A similar pin and slot connection is provided on the other end of the arc chute. The 60 arc chute is preferably of a unitary construction, as shown, having integral back and side portions, and the arrangement is 65 preferably such that the arc chute is held between the ends of the pole pieces 31 and 32 so that the back portion of the arc chute is interposed between the blow out coil 27 and the circuit interrupting switch contacts. The arcs formed between the interrupting 70 contacts are thus prevented from reaching the blow out coil, and the heat of the arcs is prevented from affecting the blow out coil. Furthermore, the unitary construction of the arc chute lends itself very readily 75 to large scale manufacture. When it is desired to remove the arc chute to replace the chute or to inspect the contacts, the bolt 27^a is backed off slightly and the chute is then freely removable. The switch 80 mechanism is mounted in a suitable base 10 of insulating material. The operating electromagnet for the switch comprises a winding 11 suitably supported within a frame 85 of magnetic material 12, and the armature 13 is pivotally supported within the frame 12 so that the arms of the armature, of 90 which only one can be seen, extend along the axis of the magnet winding 11. The projection 16 on the armature forms a support for the movable switch contact member 17. The contact finger 17 is given a wiping action with respect to the stationary contact 21 when the switch closes by means 95 comprising the pin 22 which passes through a hole in the projection 16 and a corresponding hole in the finger, and a spring 23 which passes the contact toward the projection 16. The armature 13 is pivotally supported within the frame 12, embracing the 100 winding 11, by means of a pin 24 which passes through holes in the projections on the legs of the armature and corresponding holes near the upper edges of the ends of the legs of the frame. The armature 105 is therefore biased by gravity to the position shown in Fig. 2 and is operated to the attracted position to close the switch

contacts upon the energization of the magnet winding 11, as shown in Fig. 1. This operating electromagnet is claimed specifically in my said application, Serial Number 5 361,694, filed February 27, 1920.

In accordance with the provisions of the patent statutes, I have described the principle of operation of my invention together with the apparatus which I now consider 10 to represent the best embodiment thereof; but I desire to have it understood that the apparatus shown is only illustrative, and that the invention can be carried out by other means.

15 What I claim as new and desire to secure by Letters Patent of the United States, is:—

1. The combination in a magnetic blow-out for electric switches, of a blowout coil, pole pieces therefor, an insulating arc chute 20 removably supported between the ends of said pole pieces, a pin and slot connection between the arc chute and the pole pieces, and means passing through the coil for holding the other ends of said pole pieces 25 to the coil and the arc chute between the pole pieces.

2. The combination in a magnetic blow-out for electric switches, of a blowout coil, pole pieces therefor having openings in their 30 ends, a removable insulating arc chute having projections entering the openings in the

ends of the pole pieces, and means passing through the coil for holding one end of each pole piece to the coil and the arc chute between the other ends of the pole pieces. 35

3. The combination in a magnetic blow-out for electric switches, of a blowout coil, pole pieces therefor having elongated slots in their ends, an insulating arc chute having correspondingly shaped projections entering the said slots in the ends of the pole pieces, and means passing through the said coil for holding one end of each pole piece to the coil and the arc chute between the other ends of the pole pieces. 40 45

4. The combination in a magnetic blow-out for electric switches, of a removable insulating arc chute having a projection on each side of the passage for the arc, an electromagnet, a pair of pole pieces, each 50 of which has a slot within which the corresponding projection in the arc chute enters, and one of which is secured to one end of the core of the electromagnet, and a bolt which screws into the other end of the core 55 for holding the arc chute between the pole pieces and the other pole piece to the said core.

In witness whereof I have hereunto set my hand this 28th day of June, 1921.

EUGENE R. CARICHOFF.
